UNITED STATES PATENT OFFICE.

RALPH E. CLEVELAND, OF OAKLAND, CALIFORNIA.

BRUSH.

Application filed January 31, 1922. Serial No. 533,042.

To all whom it may concern:

Be it known that I, RALPH E. CLEVELAND, a citizen of the United States, and a resident of Oakland, county of Alameda, and State of California, have invented a new and useful 5 Brush, of which the following is a specification.

The present invention relates to improvements in brushes and has particular reference to a brush to be used in connection with a wash bowl having an outlet in its bottom. The principal object of the invention is to provide means by which a person having only one hand can conveniently wash the 15 same without the assistance of another person. Ordinarily a person uses one hand to wash the other, but it is a fact that a person who has lost one hand finds it hard to wash his remaining hand without assistance. My 20 device provides a convenient means permitting a person to wash one hand by itself.

With this object in view I have illustrated the preferred form of my invention in the accompanying drawing, in which Figure 25 1 represents a vertical cross section through a wash bowl having my brush secured thereto, and Figure 2 a perspective detail view of my brush. While I have illustrated only one form of my device, it will be understood that 30 various changes or modifications may be made within the scope of the claims hereto attached without departing from the spirit of the invention.

The bowl (1), having an outlet (2) in 35 its bottom leading to the sewer and having a suitable faucet (3) secured over the same for admitting water into it, is of ordinary construction and does not offer any new features. My brush (4), which is to be used 40 in connection with this bowl and which comprises a back (6) having the bristles (7) extending therefrom, is slantingly supported within the bowl as shown in Figure 1 by means of a handle (8) secured to the back 45 of the brush by the screws (9) engaging the flange (11). The extreme end (12) of

the handle is adapted to be inserted into the outlet pipe (2) and is arrested in its downward motion by a collar (14) engaging the surface surrounding the outlet. 50

While I do not wish to be confined to the slanting position of the brush, I deem the same preferable as lending itself more readily and naturally to the use to be made of it. The manipulation of the brush is 55 easily understood. A person wishing to wash a single hand needs only to insert the brush into the outlet pipe (2) in its proper position, then open the faucet to fill the wash bowl with water and he may then 60 clean his hand by means of the brush. After he has finished the operation he may remove the brush, whereupon the water will run down through the outlet. In this manner the brush serves at the same time the purpose 65 of a plug.

I claim:

1. In combination with a wash bowl having an outlet therein, a brush having means thereon engaging the outlet for supporting 70 the brush transversely over the outlet, for the purposes set forth.

2. In combination with a wash bowl having an outlet therein, a brush having a handle provided on its back adapted to engage 75 the outlet so as to support the brush transversely over the outlet.

3. In combination with a wash bowl having an outlet therein, a brush having a handle rising from its back in a slanting direction adapted to engage the outlet for slantingly supporting the brush over the outlet. 80

4. In combination with a wash bowl having an outlet therein, a brush having a handle rising from its back in a slanting direction adapted to engage the outlet for slantingly supporting the brush in an operative position over the outlet, a collar being secured on the handle engaging the surface surrounding the outlet for maintaining the 90 brush at a desired level.

RALPH E. CLEVELAND.
